UNITED STATES PATENT OFFICE.

RUDOLPH LIEBMANN, OF NEW YORK, N. Y.

DESIGN FOR A BUTTON.

No. 40,117.

Specification for Design.

Patented July 6, 1909.

Application filed May 22, 1909. Serial No. 497,815. Term of patent 3½ years.

To all whom it may concern:

Be it known that I, RUDOLPH LIEBMANN, a citizen of the United States, residing at New York, in the county of New York and State of New York, have invented a new, original, and ornamental Design for Buttons, of which the following is a specification, reference being had to the accompanying drawing, forming part thereof.

The figures of the said drawing clearly show my new, original and ornamental de-

sign; and in the drawings, Figure 1 is a front face view, and Fig. 2 is a side view, showing my new, original and ornamental design.

I claim:—

The ornamental design for a button, as shown.

RUDOLPH LIEBMANN.
